UNITED STATES PATENT OFFICE.

JOHN B. DEEDS AND WILLIAM MACK, OF TERRE HAUTE, INDIANA.

GRINDING-MACHINE.

SPECIFICATION forming part of Letters Patent No. 497,567, dated May 16, 1893.

Application filed November 10, 1892. Serial No. 451,527. (No model.)

To all whom it may concern:

Be it known that we, JOHN B. DEEDS and WILLIAM MACK, citizens of the United States, residing at Terre Haute, in the county of Vigo 5 and State of Indiana, have invented certain new and useful Improvements in Grinding-Machines; and we do hereby declare the following to be a full, clear, and exact description of the invention, such as will enable others skilled in the art to which it appertains to make and use the same.

This machine relates to machines for grinding reaper knives, plow points, saw teeth and other similar cutting tools; and it consists in 15 the novel construction and combination of the parts hereinafter fully described and claimed.

In the drawings: Figure 1 is a side view of the machine. Fig. 2 is a front view of the arm which carries the grinding wheel. Fig. 20 3 is a section taken on the line $x-x$ in Fig. 2. Fig. 4 is a plan view, from above, of the feeding devices.

A is the base plate of the machine.

B is a bracket secured to the base plate and 25 provided with the two bearings $b-b'$.

C is the toothed driving wheel provided with a handle a . The hub a' of the driving wheel runs loose upon the outer end of the shaft C' , between the collar c' and the bearing b .

B is an arm which carries the grinding wheel. This arm is provided with a half bearing d at its upper end, and d' is a clip provided with a similar half bearing and secured to the arm by the bolts D' . The arm is clamped tightly to the shaft C' between the bearings $b-b'$. The lower end of the arm D is forked and is provided with bearings e for the shaft E of the grinding wheel to run in.

40 The grinding wheel E' is secured on the shaft E between the bearings e , and e' is a toothed pinion secured on one end of the shaft E and gearing into the wheel C. The other end of the shaft E is provided with a nut f and washers f' so that another grinding wheel can be attached to it when required, for use when the wheel E' cannot conveniently be used in

grinding some forms of cutting tools or plow points.

G is a spring secured to the arm D and to 50 the bracket B, for pressing the grinding wheel on the work.

G' is a crossbar on the bracket B, and g is a screwed stop-rod provided with a thumb-piece g' for turning it. The adjustable rod 55 g is screwed through a hole in the crossbar, and the arm D rests against the front end of the rod when the grinding wheel is in its lowest desired position.

H are guides secured to the base plate. 60

H' is a slide which moves back and forth in the guides H. The slide H' is provided with clamping devices h of approved construction for securing the work to it.

I is a horizontal hand-lever pivoted on the 65 pin i projecting from the base plate, and J are links pivotally connecting the lever I with the rear end of the slide H'.

The work is moved back and forth under the revolving grinding wheel by means of the 70 hand-lever until the arm D touches the stop rod g . When the work is pushed under the grinding wheel, it raises the grinding wheel slightly, and the shaft C' is turned in the bearings $b-b'$, but this motion of the shaft 75 does not interfere with the grinding because the driving wheel C runs loose upon the end of the said shaft. Clamping the arm D to the shaft and carrying the shaft ends in bearings makes the grinding wheel run very 80 true, and as the motion of the shaft in the bearings is very slight, the bearings do not become worn and allow the grinding wheel to have side play.

What we claim is—

1. In a grinding machine, the combination, with a supporting bracket provided with a crossbar and with bearings $b-b'$, of the shaft C' pivoted in the said bearings, the arm secured on the said shaft, the grinding-wheel shaft journaled in the free end of the said arm, the toothed pinion secured on the grinding-wheel shaft, the toothed driving-wheel journaled on the shaft C' and gearing into

the said pinion, and an adjustable stop-rod screwed into the said crossbar and operating to limit the downward motion of the said arm, substantially as set forth.

5 2. In a grinding machine, the combination, with the supporting bracket provided with a crossbar, of the arm, for carrying the grinding wheel, pivoted to the top of the said bracket, and the adjustable stop-rod for limiting the motion of the said arm, said rod being pro-

vided with the thumb-piece for revolving it and being screwed through a hole in the said crossbar, substantially as set forth.

In testimony whereof we affix our signatures in presence of two witnesses.

JOHN B. DEEDS.
WILLIAM MACK.
